United States Patent Office

Des. 185,927

Patented Aug. 18, 1959

185,927

LID FOR A WASTE RECEPTACLE

James F. Warren, Toronto, Ontario, Canada, assignor to
General Steel Wares Limited, Toronto, Ontario, Canada

Application April 3, 1959, Serial No. 55,331

Term of patent 14 years

(Cl. D58—17)

FIG. 1.

FIG. 2.

Figure 1 is a perspective view of a lid for a waste receptacle embodying the new design; and

Figure 2 is a plan view thereof.

The sides not shown are the same as the sides shown.
I claim:

The ornamental design for a lid for a waste receptacle, substantially as shown and described.
